UNITED STATES PATENT OFFICE.

HARRY S. McCORMACK, OF PROVIDENCE, RHODE ISLAND, ASSIGNOR TO
UNDERWOOD TYPEWRITER COMPANY, OF NEW YORK, N. Y., A COR-
PORATION OF NEW JERSEY.

TYPE-WRITING MACHINE.

No. 829,989.

Specification of Letters Patent.

Patented Sept. 4, 1906.

Application filed October 24, 1905. Serial No. 284,172.

To all whom it may concern:

Be it known that I, HARRY S. McCORMACK, a citizen of the United States, residing in Providence, in the county of Providence and State of Rhode Island, have invented certain new and useful Improvements in Type-Writing Machines, of which the following is a specification.

This invention relates to the paper-handling devices in type-writing machines, and especially those in which the types strike upon the front or other visible side of a cylindrical platen.

It is customary in many retail establishments to render bills to customers at long intervals, but to enter the items upon said bills at the time when the goods are sold. It is thus necessary where the bills are made out on writing-machines to insert the same bill in the machine once for each item, so that in many cases a bill has to be inserted and removed from the machine a great many times in the course of a week or month. After the first item has been written and the bill removed from the machine it becomes necessary to replace the bill in the machine accurately with reference to the printing-point, so that the second item will fall precisely in alinement with the first in order to preserve an even appearance of the columns of writing and figures. Heretofore it has been necessary each time that a bill was inserted to adjust the bill until the previously-written line thereon registers gradually with the usual platen-scale. While this adjusting operation is but a small matter, still where the bills are inserted and removed from the machine once for each item written thereon the necessity of adjusting the bill in the usual manner becomes highly objectionable.

The object of my invention is to avoid the necessity for such adjustment and to enable the bills when put in the machine to be adjusted instantly and without appreciable labor or attention to exactly the required position with reference to the printing point or line and also with reference to the usual tabulating mechanism which is commonly employed in writing bills.

In carrying out my invention I provide at the delivery side of the revolute platen a gage, against which the leading edge of the paper may abut as it emerges from the ma-

chine, and I also provide one or two gages for the side edges of the paper, and preferably I provide in connection with said gages a plate or tablet extending along the top of the platen and fixed upon the carriage-frame, for convenience in adjusting the paper to the gages.

In the accompanying drawings, Figure 1 is a perspective view of an "Underwood" type-writer carriage, showing my improvements applied thereto. Fig. 2 is a sectional side elevation of the device.

In said Underwood machine a revolute cylindrical platen 1 is mounted in ends 2 3 of the platen-frame, which is mounted upon a carriage 4. Extending between said ends is a bar 5, upon which is mounted a tablet or plate 6, which extends along the platen and overhangs the rear thereof. At its rear edge said plate is bent up to form a ledge 7 to serve as a gage against which the leading edge of the paper may abut, and at its sides said plate is bent up to form ledges 8 9, constituting gages for the side edges of the paper.

In operation a bill or sheet 10 is inserted between the platen and the usual rear inclined paper-shelf 11 and passes up around the front of the platen and back over the same. The usual pressure-rollers 12 13 being cast off in the usual manner by depressing a lever 14, the operator presses the leading portion of the paper down upon the tablet 6 and adjusts the paper so that its leading edge, as at Fig. 2, abuts against the gage 7. When introduced into the machine, the paper is passed between side gages 15 16, extending down from said rod 5, so that when it reaches the top or delivery side of the platen it is approximately correct in position with reference to the gages 8 9; but the latter are closer together than the gages 15 16 and may be so related that the paper fits accurately between them. This operation of inserting and adjusting the paper can be accomplished very quickly and without labor or thought, and it will be understood that no matter how many times the same bill is inserted it always comes to exactly the same place with reference to the printing-point, which in this instance is the front of the platen where the types 17 strike. When the paper is so adjusted, the handle 14 may be lifted, thus bringing the pressure-rollers 12 13 into action, and thereupon the

platens may be rotated by the finger-wheel 18 forwardly until the last previously-written line is brought to or above the printing-point. Thus it will be seen that the bill is always adjusted with absolute accuracy with reference not only to the printing-point, but also to the usual tabulating mechanism, so that the operator is called upon to give but a minimum of attention to positioning the paper, and hence a relatively large amount of work of this class may be accomplished in a given time. The invention is of particular value where carbon copies of the bills are made upon sheets of greater width than the bills, the gages 8 and 9 being so spaced that the large sheets fit between them, while the narrow bills may be set against either gage 8 or 9, as the case may be. It will be seen at Fig. 2 that the plate 6 and gage 7 are below the path 19, usually taken by the paper in emerging from the machine, so that the gage 7 does not interfere with the advance of the paper.

The gages and tablet may be variously formed and mounted, and in some cases the tablet may be omitted. It is not necessary in all cases that the side gages be employed in connection with the front gage 7. In some cases one of the side gages may be omitted.

It will be seen that the gages are in plain sight, so that the manipulation of the paper can be both quick and exact. When one item or charge is written, the pressure-roll-release key 14 is depressed, thereby dropping the pressure-rolls away from the platen to permit the withdrawal of the sheet, and while said rolls remain released the next sheet is slipped down between the platen and the plate 11 and around beneath and up in front of the platen, when the leading portion is pressed by the operator down upon the tablet 6 and adjusted to the gages. Then the key 14 is lifted and the platen turned until the proper point upon the bill is brought to printing position. It will be understood that the usual releasable means 19^a are employed in said Underwood machine for guiding the sheets up in front of the platen. The operation of slipping the paper around the platen is performed very quickly and much rolling of the platen is also saved, which is an advantage, since it is the practice to insert a carbon and a record sheet together with the bill, and as the bill may be inserted twenty or thirty times before completion it will be seen that it is a desideratum to avoid much rolling of the platen at each insertion, because it tends to injure or wrinkle the carbon-paper and to cause the latter to offset unduly upon the record-sheet.

Having thus described my invention, I claim—

1. In a type-writing machine, the combination with a revoluble platen, of means for securing accurate register of the sheet prepar-

atory to writing the page, comprising a plate surmounting the platen and having along its side and rear edges, ledges to serve as gages for the leading and side edges of the paper.

2. In a type-writing machine, the combination with a revoluble platen, of means for securing accurate register of the sheet preparatory to writing the page, comprising a plate surmounting the platen and having a gage at its rear portion to gage the leading edge of the paper.

3. In a type-writing machine, the combination with a revoluble platen, and releasable means for holding a sheet against the platen, of means for securing accurate register of the sheet preparatory to writing the page, comprising a plate surmounting the platen and having a gage at its rear portion to gage the leading edge of the paper, and also having a gage at one side edge to gage the side edge of the paper.

4. In a type-writing machine, the combination with a revoluble platen, of means for securing accurate register of the sheet preparatory to writing the page, comprising a plate surmounting the platen and having a gage at its rear portion to gage the leading edge of the paper, and also having gages at both side edges.

5. In a type-writing machine, the combination with a revoluble platen, and releasable means for holding a sheet against the platen, of means for securing accurate register of the sheet preparatory to writing the page, comprising a box-like structure surmounting the platen and, in advance of the printing-point, to receive and gage the paper longitudinally and laterally.

6. In a type-writing machine, the combination with a revoluble platen, of means for securing accurate register of the sheet preparatory to writing the page, comprising stationary gages surmounting the platen for both the leading and side edges of the paper.

7. In a type-writing machine, the combination with a revoluble platen and releasable means for holding a sheet against the platen, of means for securing accurate register of the sheet preparatory to writing the page, comprising stationary gages surmounting the platen for the leading edge and side edges of the paper.

8. In a type-writing machine, the combination with a revoluble platen, of means for securing accurate register of the sheet preparatory to writing the page, comprising stationary gages surmounting the platen for both the leading and side edges of the paper; said gages being mounted in such position that the paper in emerging from the machine may pass thereover.

9. The combination with a revoluble platen and types, of means for securing accurate register of the sheet preparatory to writing the page, comprising a gage for the lead-

ing edge of the paper, mounted close to the platen at the delivery side thereof, and so near the printing-point that when the sheet is in registry with said gage, the line of writing 5 will fall upon the sheet near its top edge.

10. The combination with a revolute platen, and releasable means for holding a sheet against the platen, of means for securing accurate register of the sheet preparatory to writing the page, comprising a gage for the leading edge of the paper mounted at the delivery side of the platen; said gage being in such a position that the paper in emerging from the machine may pass thereover.

15. 11. The combination with a revolute platen, of means for securing accurate register of the sheet preparatory to writing the page, comprising gages at the delivery side of the platen, for the leading and side edges 20 of the paper, said gages being so near the printing-point that when the sheet is in registry therewith, the line of writing will fall upon the sheet near its top edge.

12. The combination with a revolute platen, of means for securing accurate register of the sheet preparatory to writing the page, comprising gages at the delivery side of the platen, for the leading and side edges of the paper; said gage for the leading edge of 30 the paper being so mounted that the paper may be registered thereby and may then pass thereover in advancing out of the machine.

13. In a type-writing machine, the combination with a platen, of a gage at the feeding-in side of the platen for the side edge of the paper, and a gage at the delivery side of the platen for the front edge of the paper.

14. In a type-writing machine, the combination with a platen, of a pair of gages at the feeding-in side of the platen for the side edges

of the paper, and a pair of closer gages at the delivery side of the platen for the side edges of the paper.

15. In a type-writing machine, the combination with a platen, of a gage at the feeding-in side of the platen for the side edge of the paper, and gages at the delivery side of the platen for the front and side edges of the paper. 45

16. In a type-writing machine, the combination with a platen, of a pair of gages at the feeding-in side of the platen for the side edges of the paper, and gages at the delivery side of the platen for the front and side edges of the paper. 50

17. In a type-writing machine, the combination with a platen, of a gage at the feeding-in side of the platen for the side edge of the paper, gages at the delivery side of the platen for the front and side edges of the paper, and a plate, adjacent to said delivery-gages, upon which the paper may be pressed when adjusting it to said delivery-gages. 55

18. In a type-writing machine, the combination with a revolute platen, and releasable means for holding paper thereon, of means for securing accurate register of the sheet preparatory to writing the page, comprising a plate mounted upon the delivery side of the platen and directly over the platen, 65 and having upturned ledges to form gages for the front and side edges of the paper, said gages being so near the printing-point that when the sheet is in registry therewith, the line of writing will fall upon the sheet near 70 its top edge.
